R. KENT,
 COMBINED TOBACCO RECEPTACLE AND PIPE CLEANER.
 APPLICATION FILED DEC. 5, 1916.
 1,242,902. Patented Oct. 9, 1917.

UNITED STATES PATENT OFFICE.

RANDAL KENT, OF ELIZABETHTOWN, PENNSYLVANIA, ASSIGNOR OF ONE-FOURTH TO
PRISCILLA E. KENT, OF WASHINGTON, DISTRICT OF COLUMBIA.

COMBINED TOBACCO-RECEPTACLE AND PIPE-CLEANER.

1,242,902.

Specification of Letters Patent.

Patented Oct. 9, 1917.

Application filed December 5, 1916. Serial No. 135,110.

To all whom it may concern:

Be it known that I, RANDAL KENT, a citizen of the United States, residing at Elizabethtown, in the county of Lancaster and State of Pennsylvania, have invented certain new and useful Improvements in Combined Tobacco-Receiptacles and Pipe-Cleaners, of which the following is a specification.

This invention relates to a combined tobacco receptacle and pipe cleaner, and more particularly to means whereby the cleaner is carried in the receptacle and secured thereto.

The object of the invention is the provision of a receptacle and cleaner, in combination with means whereby the cleaner, when not in use, may be removably inserted within the receptacle, and detachably fastened in position therein.

20 A further object of the invention is the provision of means whereby the cleaner is so positioned within the receptacle that the contents thereof are not exposed to the air, and consequently damaged.

25 These and other objects as may herein-after appear, are attained by the novel construction, combination and arrangement of parts to be specifically described and claimed in the annexed specification.

30 Referring to the drawings, in which similar reference numerals indicate like parts,

Figure 1 indicates a perspective view of a tobacco receptacle or can, showing the cleaner in position;

35 Fig. 2 is a section taken on line 2—2 of Fig. 1;

Fig. 3 is an enlarged sectional view of the lower part of Fig. 2;

40 Fig. 4 is a section taken on line 4—4 of Fig. 2;

Fig. 5 is a plan view of the bottom of the receptacle or container;

Fig. 6 is a perspective view of the cleaner, and

45 Fig. 7 is a fragmentary perspective view, showing a modified form of cleaner.

In the drawings, 1 indicates a tobacco receptacle, hereinafter called the can, of the usual construction, provided at its bottom with the usual peripheral flange 2. Snugly fitting within the can is the usual capsule 3 of paraffin paper, or of other air-proofed material, see Figs. 2 and 4. The capsule 3 contains the tobacco 4, and prevents the entrance of air thereto, and consequently preserving the tobacco in good condition. This

is the construction and arrangement of tobacco cans at present in use.

In the application of my improvement, the bottom 5 of the can is apertured at 6, 60 this aperture being preferably provided on the line of mergence between the vertical wall of the flange 2, and the bottom 5, and, also preferably, near one of the edges of the can, as clearly indicated in all the figures of 65 the drawing. Moreover, and for a purpose to be hereinafter explained, the aperture 6 is preferably so formed that the inwardly turned flange 7 thereof is upwardly beveled or inclined, as indicated in Figs. 2, 3 70 and 4.

The cleaner 8 may be of any desired construction. I prefer to construct it of a fairly resilient, corrugated wire, as shown in Fig. 6, and, if desired, it may be covered partly or wholly with felt or other absorbent. It is preferably formed of a material which is possessed not only of an inherent resiliency, but is also sufficiently rigid for the purposes to be hereinafter described. 75

The outer end 9, or handle of the cleaner, is turned at approximately a right angle to the body portion, and terminates in an angled extension 10, as shown in the drawings. 80

85 From the foregoing the operation of my device is clear. The cleaners may be applied in position at the factory, when the tobacco is packed in the cans, or the can may be pierced by the consumer and the cleaners made and properly positioned, or the cleaners may be bought in the open market. In any event the body portion of the cleaner is inserted in the aperture 6, and extends upwardly within the can, between a side wall 95 thereof and the air-proof capsule 3. It will be noted, see Figs. 2 and 3, that the lower portions of the capsule 3^a are rounded at the bottom, greatly facilitating the insertion of the cleaner between the wall and the capsule 100 without danger of rupture of the latter.

It will be understood that, with the body of the cleaner between the wall and capsule, due to the proper proportioning of the parts, the handle 9 will be upon the bottom 105 5. The cleaner may then be rotated so that the handle 9 may extend across the bottom 5, and the angled extension 10 will then frictionally engage the flange 2. A slight pressure to the right, when the device is 110 in the position shown in Fig. 5, will partly flex the handle 9 to the position shown in

dotted lines, and will cause increased pressure or friction between the flange 2 and extension 10. I have shown in the drawings a further means to insure the retention 5 of the cleaner in position, the flange 2 being hammered or bent inwardly slightly, at 11, to extend over the extension 10. This construction has its advantages, but is not absolutely essential, as the resiliency of the 10 material of the cleaner will satisfactorily hold it in position when the parts are properly proportioned.

A modification of the form of cleaner is shown in Fig. 7, in which the extension 10 is longer. In this arrangement the aperture 6 is so positioned that pressure upon the handle 9 will cause the end of the extension 10 to engage the flange 2 at 2^a, whereby the handle 9 and extension 10 are both flexed, 20 and very effectually prevent accidental rotation of the cleaner 8. In any case a slight movement of the handle 9 to the left, see Figs. 5 and 7, will release the engagement between the extension 10 and flange 2, 25 and admit of rotation and removal of the cleaner 8.

It will be observed that the handle portion of the cleaner, when the cleaner is in its secured position, rests above the lower 30 edges of the flange 2, and consequently, in handling the can, placing it in the pocket or taking it therefrom, etc., the probability of rotation of the cleaner and consequent displacement and loss thereof, is reduced to 35 the minimum.

It is to be noted also that, in use by the consumer, the point of the cleaner is placed upon the line of mergence between the flange 2 and bottom 5. The point is merely moved 40 along this line and toward the aperture 6 which on account of the bevel thereof, is easily located for the insertion of the cleaner. The cleaner is then pushed upwardly in the can, between the capsule and wall, as before stated. The packed tobacco exerts a pressure upon the capsule, offering some resistance to the passage of the cleaner. This resistance may be utilized in 45 freeing the cleaner of nicotin and other foul matter brought from the pipe stems, the cleaner being rotated for this purpose. In fact, the slight rotation necessary for 50 locking and unlocking the handle is sufficient to purge the cleaner. Since the capsule is waterproof the deposits left thereon by the cleaner cannot reach and injure the 55 tobacco contained in the can.

From the foregoing it will be clear that I have devised a construction of a cleaner 60 which is well adapted for combination with the can at present in use, and one which is exceedingly economical from an installation standpoint, and efficient in operation.

Various embodiments may be suggested to those skilled in the art, but I do not confine 65 myself to the preferred structure here shown but desire to secure by Letters Patent all such modifications as fall fairly within the scope of the appended claims.

What I claim and desire to secure by Let- 70 ters Patent is—

1. The combination with a receptacle for smoking tobacco and provided with a flange at one of its ends, of a pipe cleaner adapted for insertion through one of the walls of 75 said receptacle, and to lie between a wall of the receptacle and the contents thereof, said cleaner being shaped to provide means adapted to engage said flange, whereby the cleaner is detachably held within the recep- 80 tacle.

2. The combination with an apertured receptacle for capsuled smoking tobacco and provided with a marginal flange at one of its ends, of a relatively resilient pipe cleaner 85 adapted for insertion through said end wall, and to lie within the receptacle between a side wall and the capsuled tobacco, said cleaner being provided on its outer end with a resilient angled portion adapted to en- 90 gage said marginal flange and detachably hold the cleaner in its inserted position.

3. The combination with a receptacle containing a tobacco capsule and having side and end walls, one of the latter being provided with a peripheral flange, of a pipe cleaner adapted for insertion through said end wall, adjacent said flange, and to extend within the receptacle between said capsule and a side wall, said cleaner being provided with an extension angularly disposed with respect to the body portion thereof, said extension resting upon the outside of the end wall and lying wholly within a plane between the end of the receptacle and 105 the edge of the flange, said extension engaging said flange, whereby the cleaner is detachably secured in position within the receptacle.

4. The combination with a smoking to- 110 bacco receptacle provided with a marginal flange having an offset portion, of a pipe cleaner adapted for insertion within said receptacle and having at its outer end an extension engaging said flange and resting 115 between the end of the receptacle and said offset portion, whereby the cleaner is detachably held within the receptacle, substantially as described.

In testimony whereof I affix my signature in the presence of two witnesses.

RANDAL KENT.
